EYE SHADE WITH REMOVABLE CROWN

Erline L. Huffman, 7350 Deep Run,
Birmingham, Mich. 48010

Filed Nov. 24, 1972, Ser. No. 309,185

Term of patent 14 years

Int. Cl. D2—03

U.S. Cl. D2—244

FIG. 1 is a side elevational view of an eye shade with removable crown showing my new design, the side opposite being a mirror image thereof;

FIG. 2 is a bottom plan view thereof on a reduced scale with the crown portion removed;

FIG. 3 is a top plan view thereof;

FIG. 4 is a side elevational view; and

FIG. 5 is a front perspective view thereof on an enlarged scale.

I claim:

The ornamental design for an eye shade with removable crown, as shown and described.
